UNITED STATES PATENT OFFICE.

SAMUEL BOUTON, OF PHILADELPHIA, PENNSYLVANIA, ASSIGNOR OF ONE-HALF TO WILLIAM F. RUWELL AND ALFRED HENWOOD, OF SAME PLACE.

EXPLOSIVE-ENGINE.

SPECIFICATION forming part of Letters Patent No. 606,504, dated June 28, 1898.

Application filed July 30, 1897. Serial No. 646,440. (No model.)

To all whom it may concern:

Be it known that I, SAMUEL BOUTON, a citizen of the Republic of France, residing at the city of Philadelphia, in the county of Philadelphia and State of Pennsylvania, have invented certain new and useful Improvements in Air and Vapor Engines, of which the following is a specification.

My invention has relation to an air and vapor engine; and in such connection it relates particularly to the construction and arrangement of such an engine.

The principal object of my invention is to provide an air and vapor engine of comparatively simple construction, efficient in action, and economical in operation.

My invention, stated in general terms, consists of an air and vapor engine constructed and arranged in substantially the manner hereinafter described and claimed.

The nature and scope or characteristic features of my invention will be more fully understood from the following description, taken in connection with the accompanying drawings, forming part hereof, in which—

Figure 1 is a side elevational view of an air and vapor engine embodying main features of my invention. Fig. 2 is a top or plan view of the same, partly sectioned, on a horizontal plane. Fig. 3 is an elevational view, enlarged and partly sectioned, of the left-hand end of the machine; and Fig. 4 is a vertical sectional view, enlarged, of the vapor-chamber and connections.

Referring to the drawings, A represents the framework of the engine, in which is supported the cylinder B, the fly-wheel C, and its crank-shaft C'. The cylinder B is surrounded by the ordinary water-jacket B', and the crank-shaft C' is attached by the connecting-rod C² with the piston B² in the usual manner. The cylinder-head a is provided with two ports b and d, each closed by preferably a spring-controlled conical valve b' and d', respectively. The port d is the exhaust-port and communicates by a pipe d² with an exhaust-pot d³ of the ordinary construction. The port b is the inlet-port to the cylinder for the introduction of mixed air and vapor, and it is connected by a pipe b² with

a mixing-chamber e, preferably situated above and in communication with a reservoir f, wherein the volatile or easily-vaporized liquid is stored. As illustrated in Fig. 4, the upper end of the mixing-chamber e is provided with an inlet e', controlled by a spring-controlled valve e², the inlet communicating with the open air or any suitable source of air-supply. The pipe b², leading from the combustion end of the cylinder B, extends downward into the mixing-chamber e below the air-inlet e' and directly above an opening or inlet f', controlled by a valve or cock f² and leading to the reservoir f.

The spring-controlled valve b' is so regulated that upon the out or exhaust stroke of the piston B² the vacuum created in the cylinder B will cause the valve b' to momentarily open and exhaust a charge from the mixing-chamber into the cylinder. The air-valve e² is likewise so regulated that it will open momentarily when a partial vacuum is created in the mixing-chamber upon the opening of the charging-valve b' and will permit of the momentary inflow of air to the said mixing-chamber. The cylinder B is also provided with a port g, leading to an ignition apparatus, consisting of a nipple g', surrounding the port and adapted to be heated to redness by a burner g², as indicated in Fig. 3 of the drawings.

Upon the shaft C' of the engine is secured a gear-wheel D, meshing with the gear-wheel D', to which is eccentrically pivoted a connecting-rod D², adapted to actuate a slide D³, carrying a finger or projection D⁴, adapted to strike against the stem of the valve d, and thereby open said valve directly after the explosion of the air and vapor in the combustion-chamber B³.

The operation of the engine hereinbefore explained is as follows: Upon the out stroke of the piston a partial vacuum is created in the cylinder, resulting in the opening of the valve b' and the creation of a partial vacuum in the mixing-chamber and reservoir f by the suction of a charge from the mixing-chamber to the cylinder. The vacuum in the mixing-chamber causes the air-valve e² to open, admitting a charge of air to the mixing-chamber.

ber, and also causes a charge of vapor to pass from the reservoir *f* to the mixing-chamber, the vaporization of the liquid in the reservoir *f* being assisted or accelerated by the partial 5 vacuum in the reservoir. Upon the in or return stroke of the piston, the valve *b'* being closed, the charge is compressed and a portion is forced through the port *g* to the ignition apparatus, and thereby exploded. At the 10 moment of explosion the port *d* is opened and the exhaust or spent products of combustion escape to the exhaust-pot *d'*.

Having thus described the nature and objects of my invention, what I claim as new, 15 and desire to secure by Letters Patent, is—

In an air and vapor engine, the combination with the cylinder and piston, of a mixing-chamber having at its upper end a valve-controlled inlet for the entrance of air, a pipe

leading from the cylinder to the mixing-chamber below the air-inlet thereof, a valve controlling said pipe and a vapor-reservoir in open communication with the mixing-chamber below said pipe, said valves controlling respectively the air-inlet to the mixing-chamber and the pipe leading to the cylinder being so arranged that upon the creation of a partial vacuum in the cylinder each valve will automatically open, substantially as and for the purposes described. 20 25 30

In testimony whereof I have hereunto set my signature in the presence of two subscribing witnesses.

SAMUEL BOUTON.
